UNITED STATES PATENT OFFICE.

SAMUEL K. DRUCE, OF MADEIRA, OHIO, ASSIGNOR OF ONE-THIRD TO
ARTHUR C. DINGELSTEDT, OF CINCINNATI, OHIO.

PRINTING ATTACHMENT FOR ROLL-PAPER.

SPECIFICATION forming part of Letters Patent No. 651,414, dated June 12, 1900.

Application filed January 31, 1900. Serial No. 3,441. (No model.)

To all whom it may concern:

Be it known that I, SAMUEL K. DRUCE, a citizen of the United States of America, and a resident of Madeira, in the county of Hamilton and State of Ohio, have invented certain new and useful Improvements in Printing Attachments for Roll-Paper, of which the following is a specification.

This invention relates to certain improvements in printing attachments for roll-paper, and has for its object to provide a device of this nature which shall be of a simple and inexpensive character and of a construction strong and durable and which shall be capable of being readily applied, if desired, to roll-paper holders such as are in common use or of being manufactured as a part of such roll-paper holders.

The invention consists in a device of this character comprising a printing attachment for printing the paper from the roll and means for automatically removing said attachment from printing contact with the paper after each operation of the attachment.

The invention also contemplates certain novel features of the construction, combination, and arrangement of the several parts of the improved printing attachment, whereby certain important advantages are attained and the device is made simpler, cheaper, and otherwise better adapted and more convenient for use, all as will be hereinafter fully set forth.

The novel features of the invention will be carefully defined in the claims.

In the accompanying drawings, which serve to illustrate the invention, Figure 1 is a rear elevation of a paper-roll holder having my improvements applied thereto, and Fig. 2 is an end elevation of the same. Fig. 3 is an enlarged partial end view of the printing attachment, the hand-wheel of the type or printing roller being omitted. Fig. 4 is an enlarged partial sectional view taken vertically through the printing attachment in the plane indicated by line 4^a 4^a in Fig. 1. Fig. 5 is an enlarged transverse section taken through the type or printing roller of the attachment in the plane indicated by the line 5^a 5^a in Fig. 1. Fig. 6 is an enlarged partial view showing one of the bearings for the ends of the printing-roller. Fig. 7 is an enlarged partial sec-

tion taken along one of the slotted guides of the attachment. Fig. 8 is an enlarged detail view showing one of the clamping-blocks for holding the end bearings of the printing-roller in place on the slotted guides.

As shown in the views, the roll-paper holder is of a well-known construction, having uprights or standards 11, connected at their upper ends by a cross-bar 2, and having centrally-arranged open bearings 3 3, in which are held the ends of a shaft 4, on which the paper-roll 5 is carried. The device is also provided with a blade 6, along which the paper may be torn, said blade being held by spring-actuated arms 7, so as to press at all times on the front face of the roll 5.

8 indicates the type or printing roller of the printing attachment, said roller being held on a shaft 9, held to turn in openings 10 in bearing-plates or slides 11, one at each end of the roller. The bearing-plates or slides 11 have each two parallel channels 12 12, spaced apart to receive the arms 13 13 of slotted or forked guides, one at each end of the roller 8, said arms 13 being spaced apart by slots 14, in which play the thicker central parts 15 of the plates or slides 11 when said plates or slides are moved up or down along their guides, as is required in order to accommodate the printing attachment to the gradually-decreasing diameter of the paper-roll 5. The guides have their lower ends 15 perforated for the passage of the shaft 4, on which they are held at opposite ends of the paper-roll 5, and said guides stand in a rearwardly-inclined position, their upper ends being secured to the cross-bar 2 by means of curved braces 16, as shown in Fig. 2.

The bearing-plates or slides 11 are each held to its guide by means of an attached plate 17, riveted or otherwise secured to it and extended across the upper ends of the channels 12, these plates 17 being omitted in Figs. 6 and 7 to show the channels 12 beneath. The ends of shaft 9 project outside the bearing or slide plates 11 and serve to receive hand-wheels 18, as shown in Figs. 1, 2, and 3, by means of which the shaft and the type-roller 8, carried thereon, may be turned, as will be hereinafter explained.

Spiral springs 19 are arranged in the slots 14 above each slide-plate 11, said springs hav-

ing their lower ends engaged with upwardly-extended pins 20 on said slide-plates and having their upper ends engaged with similar downwardly-extended pins 21 on clamping-blocks 22, which have their opposite side portions recessed or reduced in thickness, as shown at 23 in Fig. 8, to receive the arms 13 of the slotted guides and have thickened portions 24 between said recessed side portions 23 to fit in the slots 14 of the guides. The clamping-blocks 22 are also provided with clamping-plates 25, adapted to extend over the recessed side portions 23 and the arms 13, held therein, being secured to the blocks 22 by means of thumb-screws 26, which serve to press the plates 25 on the blocks in order to clamp and hold the latter in adjusted position on the slotted guides. By this construction when it is desired to shift the position of the clamping-blocks up or down on the guides it is only necessary to loosen and not to entirely remove the screws 26. The pins 20 and 21 are made in tapered form, as shown clearly in Figs. 6, 7, and 8, in order to permit 25 of being pressed tightly inside the ends of the springs 19 and by a wedging action to secure the plates 11, blocks 22, and springs 19 together for movement along the guides.

The bearing-plates or slides 11 have rearwardly-extended arms 27, the extremities of which have angular slots 28 open at the upper sides of the arms and serving to receive the ends of a shaft 29, on which the ink-roller 32 is carried, said slots being provided with 35 springs 30, which are pressed, by means of screws 31, against the ends of the shaft 29 in such a way as to hold the ink-roller pressed elastically upon the printing-roller 8. The ink-roller 32 has at its central portion an absorbent pad 33, adapted to receive a supply 40 of ink after the fashion of a rubber-stamp pad.

The type or printing roller 8 has an enlarged or thickened central portion 34, longitudinally slotted in its periphery, as shown at 45 35, to receive removable types 36, from which the paper on roll 5 is printed, the ends of the thickened portion 34 of the roller having annular flanges or plates 37 secured thereon, which close the ends of the slots 35 in the 50 roller, so as to hold the types in place therein, and are of diameters slightly greater than that of the part 34 of the roller. The plates or flanges 37 are adapted to rest on the surface of the paper-roll 5 and are notched or serrated 55 in order to insure the rotation of the printing-roller from the movement of the paper-roll when the paper thereon is drawn endwise under the blade 6. The flanges or plates 37 are also adapted for contact with the ink-pad 33

60 of the ink-roller 32, so as to insure the rotation thereof in contact with the type-surfaces of the printing or type roller 8, and the projecting teeth or serrations of said flanges will receive ink from the pad 33 and apply the 65 same to the paper of the roll 5, so as to print a line of impressions along each side of the imprint of the type-surfaces of roller 8 upon

the paper. Cam devices are also carried by the printing-roller 8 and are arranged to lift said roller, so as to remove its type-surfaces 70 from contact with the paper of roll 5 after each rotation of the said printing-roller, whereby it will be seen that instead of the printing-roller being continuously rotated from the movement of the paper-roll 5 and printing a 75 continuous series of impressions upon the paper of said roll the printing from roller 8 upon the paper, as well as the rotation of said roller and of the ink-roller 32, is automatically stopped after each full rotation of said printing-roller. The cam devices comprise plates 80 38, one at each end of the roller 8, each plate having a projecting flange 39 of rounded form and slotted at one end to receive a small roller or wheel 40, which projects beyond the perimeters of the flanges or plates 37 and is adapted in the rotation of the roller 8 to come into rolling contact with the paper-roll 5, as shown in Fig. 4.

In the operation of the device as the paper 90 from roll 5 is pulled endwise under the bar 6 the rotation of the roll will be imparted to the printing-roller 8, so as to cause the type-surfaces thereof to make an imprint upon the paper, the ink-roller 32 being simultaneously 95 rotated, so as to supply ink to said type-surfaces. When the printing-roller has completed a rotation, its cam-rollers 40, by contact with the paper-roll 5, will act to lift said printing-roller, so as to remove its type-surfaces 100 36 and flanges 37 out of printing and driving engagement with the paper-roll 5, so that the paper from said roll 5 may be drawn out to any desired length without being again printed. When it is again desired to set the 105 printing devices in operation, the roller 8 is turned slightly by means of the hand-wheels 18, so as to move the cam-rollers 40 out of contact with the paper-roll 5 and permit the type-surfaces and flanges of the type or printing 110 roller to again come in contact for printing and driving with the paper-roll 5.

The springs 19 serve to hold the type-surfaces of the printing-roller in close contact with the paper-roll 5 despite any inequalities 115 therein or the gradually-decreasing diameter of said roll, and the adjustable clamping-blocks 22 permit the tension of said springs to be varied and also permit of being moved down along the slotted guides when the diameter of the roll 5 has been greatly reduced. The slotted printing-roll 8 also permits of readily changing the type-surfaces thereof when desired; but this changeable feature forms no part of the present invention and is 120 non-essential thereto.

The arrangement of the printing-roller with projecting flanges 37, adapted for driving contact not only with the paper-roll, but also with the ink-roller 32, affords an extremely 125 simple and desirable means for imparting the necessary movement to the printing and ink rollers and also serves for the printing of parallel lines on the paper along each side of the

imprint of the main type-surfaces 36, so as to give a more ornamental effect to the imprint.

The improved printing attachment constructed as above set forth is of an extremely simple and inexpensive nature and is especially well adapted for use in connection with paper-holders, since it permits of printing but a single imprint upon the paper, instead of a continuous series of impressions, as in other devices heretofore provided for this purpose.

Also the type or printing roller stands normally with its type-surfaces raised off the paper-roll, so that whenever desired and without any manipulation of the printing attachment whatever a sheet of paper of any desired length and unprinted may be torn from the roll. It will also be obvious from the above description of my improvements that the printing attachment is capable of some modification without material departure from the principles and spirit of the invention, and for this reason I do not wish to be understood as limiting myself to the precise form and arrangement of the several parts herein set forth.

Having thus described my invention, I claim—

1. The combination of a holder adapted to carry a paper-roll, guides, a printing-roller adapted for movement between the guides toward and away from said paper-roll, a shaft whereon said printing-roller is held and having an end extended beyond the said guides, means for elastically pressing the printing-roller toward said paper-roll, a cam device for removing and holding the printing-roller out of contact with the paper-roll after each rotation of the printing-roller and a hand-wheel on the extended end of the printing-roller shaft, substantially as set forth.

2. The combination of a holder adapted to carry a paper-roll, a printing-roller adapted for movement toward and away from said paper-roll, means for pressing the printing-roller, when released, toward said paper-roll, and a cam device for removing said printing-roller from contact with the paper-roll after each rotation of the printing-roller and comprising a part projected beyond the periphery of the printing-roller for contact with the paper-roll, and a roller held to turn on one end of said projecting part and also adapted for contact with the paper-roll, substantially as set forth.

3. The combination of a holder adapted to carry a paper-roll, slotted guides at opposite ends of said paper-roll, bearing-plates mov-

able along said slotted guides and having tapered pins projected in the slots of the guides, a printing-roller having a shaft journaled in 60 said bearing-plates, adjustable blocks held for movement along the guides and provided with pins tapered and projected in the slots of the guides, and springs held in the slots of the guides between the bearing-plates and 65 said blocks and having the said pins wedged in their ends, substantially as set forth.

4. The combination of a holder adapted to carry a paper-roll, guides at opposite ends of the roll, each guide being forked to produce a longitudinal slot in it, bearing-plates movable along the guides, blocks adjustable on the guides above the bearing-plates, said bearing-plates and blocks having recesses aligned with the slots of the guides, a printing-roller having a shaft journaled in the bearing-plates, springs arranged in the slots of the guides and means for holding the ends of the springs in the recesses in the bearing-plates and blocks, substantially as set forth. 75 80

5. The combination of a holder adapted to carry a paper-roll, guides at opposite ends of the roll, each guide being forked to produce a longitudinal slot in it, bearing-plates movable along the guides, a printing-roller having a shaft journaled in the bearing-plates, 85 springs held in the slots of the guides with their lower ends engaged with the bearing-plates, blocks arranged on the guides above the springs, and clamping-plates and screws 90 carried by the respective blocks for holding them adjustably in place on the guides, substantially as set forth.

6. In a device for printing roll-paper, the combination of a printing-roller having reduced end portions and an enlarged central portion provided with longitudinal type-receiving slots, annular plates held on the roller at the ends of the enlarged central portion and extending across the ends of the slots to 100 hold the type against displacement and their edges projecting beyond the perimeter of the roller for driving engagement with a paper-roll, and cam devices carried on the reduced end portions of the printing-roller and adapted for engagement with the paper-roll for lifting the printing-roller out of engagement therewith, substantially as set forth. 105

Signed by me at Cincinnati, Ohio, this 27th day of January, 1900.

SAMUEL K. DRUCE.
